UNITED STATES PATENT OFFICE.

ALVAH L. POWELL, OF MILES CITY, MONTANA, ASSIGNOR, BY MESNE ASSIGNMENTS, TO THE A. L. POWELL POWER COMPANY, INCORPORATED, OF MILES CITY, MONTANA, A CORPORATION OF MONTANA.

INTERNAL-COMBUSTION ENGINE.

Application filed December 24, 1920. Serial No. 433,033.

My invention relates to improvements in internal combustion engines in which I effect an ultimate compression by a secondary compression means, obtaining, at the same time, a firing effect which makes an engine built according to my plans a self contained power developing structure. The form shown herein is an improvement over that given in my application bearing the 10 Serial No. 433,032. In that application, however, I show a means of operating the secondary piston from the heat of the exhaust gases, but in this I use auxiliary means, operated from the power of the 15 crank shaft.

In the accompanying drawings I show an arrangement of my improvement, together with modifications thereof.

Fig. 1 is an elevation, partly in section. 20 Fig. 2 is a cross section on the dotted line $a-b$, Fig. 1.

Fig. 3 is a modification of my invention, applied to a two cycle engine. The view is an elevation, in section.

25 Fig. 4 is an elevation of the same modification, showing it adapted to a four cycle engine.

Fig. 5 is a cross section of the modification in Fig. 4, showing the reciprocating piston and rotating piston in relative positions at end of upstroke of the reciprocating piston.

Fig. 6 shows my invention with compressed air operable means.

30 Figs. 7, 8, 9, are sectional views of the valves controlling air flow and exhaust in the construction given in Fig. 6.

In Fig. 1, a piston, C^6 , is slidable in a cylinder of a gas engine, here assumed to be 40 of the four cycle type. Slidable pistons, A^3 , A^4 , are shown, the latter moving at right angles to the piston C^6 . Inlet and exhaust valves are indicated at A^7 , A^8 . From the pistons A^3 , A^4 , piston rods, F' , F , are fitted 45 to the arms of bell cranks, F^3 , F^2 . The other arms of the bell cranks are similarly fitted to a bar, F^4 that forms part of cam rod F^5 . On the end of this rod is a cam roller D^2 , that rides on a cam D . The cam 50 is rotated by properly proportioned gears, on shafts as shown. From the piston C^6 movement is imparted to the shaft C^7 by the conventional means shown.

At the end of upstroke of the power pis-

ton C^6 , and immediately prior to the explosion, the parts are in the position given in Fig. 1. The engine crank is vertical and the piston is stationary as it pauses on the center line of shaft. At this point, and for a short time thereafter when motion is negligible by reason of the crank angle, the cam D lifts the roller D^2 . The connecting means between cam and bell cranks causes the latter to rock on their supporting pins, G , G^1 . The latter are mounted on extensions from the cylinder A' . This effects movement of the pistons A^3 , A^4 , in a direction towards each other, the space between them decreasing in volume as they advance. The compression already existing is increased by this. The parts are proportioned 55 to give an extreme compression and the heat rises to the point of combustion, the charge being fired. It is evident that this firing will always occur on the outstroke of 60 piston, and never on its upstroke, precluding pre-ignition.

In Fig. 3 I effect the same purpose by means of a rotary piston that fulfills the functions of the two reciprocating pistons 65 already described. The rotary member, H , Fig. 5, makes a part turn on the instroke of the reciprocating piston C^6 . The latter is machined out to fit H closely, while a lug, H^1 from the cylinder fits the rotary member H , as shown, assuring tightness from leakage. H is rotated by a crank, H^2 , operated by a pitman H^3 and bell crank H^4 , the latter moved in proper time by a cam. A spring H^5 provides for the return of the 70 movement to an initial position.

In Fig. 4 the same functions are filled in the same way, but the valves are arranged for a four cycle instead of a two cycle engine.

Fig. 6 shows an engine equipped as already described but in which the operating power for the secondary pistons is obtained from a compressed air pump, J , operated by a crank J^3 . Air from this pump is forced 80 into a cylinder J^1 . From this it is distributed to the secondary pistons at the proper time, through a two way valve J^2 . The timing is effected by the cam D , which lifts the cam rod D^1 , in turn operating the bell crank D^3 , by means of the rod D^1 which 85 opens the two way valve, J^2 , permitting compressed air to flow through pipe C .

2
On release of cam rod by cam D the air port is thrown to exhaust (Figs. 7, 8). Fig. 9 shows the valve when compressed air is passing to the reciprocating pistons.

5. What I claim is new, and ask to have protected by Letters Patent, is—

10. 1. In an internal combustion engine, a power cylinder, a power piston, inlet and outlet valves, cylindrical spaces in the head of said power cylinder and at right angles thereto, pistons in said cylindrical spaces, rods from said pistons projecting beyond said cylindrical spaces, bell cranks, supporting lugs from the engine for said bell cranks, 15 springs from said bell cranks, supporting lugs on said engine to hold said springs; a yoke, a bar carrying said yoke, a guide for said bar, connecting means from said yoke to said bell cranks, connecting means from said bell cranks to said rods, a roller on said bar, 20 a cam shaft, means for moving said roller by the action of said cam shaft, a power shaft,

and means for rotating said power shaft by the movement of said power piston, substantially as described.

25 2. In an internal combustion engine, a power cylinder, a power piston slidable therein, a crank shaft, means operatively connecting said piston with said crank shaft, a secondary cylinder, a piston slidable therein, a bell crank lever, means operatively connecting said last mentioned piston with said bell crank lever, supporting means for said bell crank lever, a cam, means operatively connecting said cam with said crank shaft, and a rod operatively connected to said bell 30 crank lever, said rod being engaged by said cam and operated thereby, the cam having a periphery of such a contour so that the piston slidable in the secondary cylinder is held stationary during the firing stroke of the primary piston.

35 In testimony whereof I affix my signature.
ALVAH L. POWELL.
